RICHARD E. BISSELL, OF CLEVELAND HEIGHTS, OHIO, ASSIGNOR TO THOMPSON PRODUCTS INC., OF CLEVELAND, OHIO, A CORPORATION OF OHIO

POPPET VALVE

Application filed August 2, 1926. Serial No. 126,355.

The invention relates to poppet valves of the type commonly employed in internal combustion engines.

The object of the invention is to provide a valve head having an insert of material of different characteristics from that of the main body of the head, which may be made in a simple and economical way.

The invention consists in the article hereinafter described and claimed.

In the drawings:

Figure 1 is a vertical section through a valve made in accordance with my invention, showing parts of the engine structure associated therewith.

Fig. 2 is the blank from which the valve head is formed, ready for the upsetting operation.

Fig. 3 illustrates the shape assumed by the blank after the first upsetting operation.

Fig. 4 is a plan view of the valve head as shown in Fig. 1.

Fig. 5 is a vertical section through the head of a modified form of valve in which the insert is entirely enclosed by the body of the valve head.

Referring to the drawings in detail, in which the same reference number is used throughout to designate the same part, a metal rod 1 is provided with a thickened upper end 2 in which is formed a recess 3. This recess is filled, or partially filled, with a material having characteristics different from the material of the rod 1. Preferably the rod 1 will be of non-hardened steel, capable of being worked. The material selected for the insert will depend upon the function it is to perform in the completed valve. It might be desired to make a valve with an insert of high heat conductivity for the purpose of equalizing the temperature throughout the valve head; or one having an insert of greater coefficient of expansion whereby to lift the head on its seat sufficiently to com-

pensate for an increased length of the stem, as the temperature of the parts increase in operation, or one having an insert of material of different natural free vibration than the material of the main body, for the purpose of deadening the sound resulting from

the seating of the valve; or one having an insert of still different characteristics for some other purpose. In so far as I know, an insert of metal in a valve head having characteristics different from the main body of the head is novel and I claim it broadly. But specifically the invention relates to an insert designed to reduce vibration of the valve head resulting from engagement with its seat at high velocity. To reduce vibration, many different materials may be used, the material to be selected being dependent partly upon its own characteristics and partly upon the material employed for the main body of the head. Preferably it should be soft and non-oxydizing, and with a natural free vibration differing from the remainder of the head. At the present time, I consider invar as one of the best materials for the insert where the remainder of the head is of silicon-chromium steel. But if invar were used for the main body of the head a non-ferrous metal would serve well for the insert.

Having filled the recess 3 with material such as above described, the end of the rod is subjected to an upsetting operation, well known to those skilled in the art. Preferably dies will be selected such that after the first operation the head will have the appearance indicated in Fig. 3. The blank is then subjected to a second upsetting operation to form the head as shown in Fig. 1.

While it is considered preferable to have the recess containing the insert open from the upper face of the head, the inserted material might be entirely surrounded by the main body of the head, as shown in Fig. 5. To fabricate such an article, it would only be necessary to partially fill the recess 3, leaving a space at the top, whereby in the subsequent upsetting operation, the material of the main body of the valve would be pressed entirely around the material of the insert.

It is well known that the closing of the valves of an internal combustion engine on their seats at high velocity causes considerable noise, which is due to the ringing qualities of the valve head. An insert such as described above acts materially to reduce this

vibration not only because of the character of the material selected for the insert but because the junction between the materials of the insert and main body is such as will not 5 freely transmit the vibration initiated at the margin of the valve, as would be the case were the head homogeneous; in other words, the different materials are in adhering contact, in most embodiments, as distinguished 10 from the intimate union resulting from cohesion, such as occurs in welding. The result is such as that commonly observed in a cracked bell.

It is apparent that the materials of the 15 main body of the valve head and of the insert may be widely varied, depending upon the functions which it is desired the valve shall perform. It is therefore to be understood that the disclosure herein is merely 20 exemplary of the principles underlying my invention, and that it is not confined to the specific article or mode of construction disclosed, but that it includes all changes and modifications falling within the terms of the 25 appended claims.

What I claim is:

1. As an article of manufacture a valve comprising a stem, a head thereon and an insert of a sound deadening material capable of withstanding the high temperatures 30 to which said valve is normally subjected disposed wholly within said head including a relatively thin lateral portion extending toward the peripheral edge of said head and interlocked with said head.

2. As a new article of manufacture, a two-piece, interlocked headed member adapted 40 for use at high temperature, comprising a stem, a head thereon and an insert of a sound-deadening material capable of withstanding the high temperature to which said headed member is subjected while in use, in said head and interlocked therewith.

Signed by me this 21st day of July, 1926.

RICHARD E. BISSELL.
